UNITED STATES PATENT OFFICE.

OLIVER H. CLOYD, OF KANSAS CITY, MISSOURI, ASSIGNOR TO THOMAS E. GAINES, OF KANSAS CITY, MISSOURI.

CULTIVATOR.

No. 796,401.

Specification of Letters Patent.

Patented Aug. 1, 1905.

Application filed November 15, 1904. Serial No. 232,793.

To all whom it may concern:

Be it known that I, OLIVER H. CLOYD, a citizen of the United States, residing at Kansas City, in the county of Jackson and State of Missouri, have invented certain new and useful Improvements in Cultivators, of which the following is a specification.

This invention relates to lister-cultivators of that class embodying wheels as a support instead of runners, and has for its object to generally improve that type of lister-cultivators in which the weight of the driver and cultivating appliances and the draft of the team is utilized to assist in embedding the cultivating appliances in the soil; and my special object is to produce a machine of the type mentioned which minimizes the power to be applied on the lever in the disposal of the cultivating appliances in operative or inoperative position.

With the end in view named the invention consists in certain novel and peculiar features of construction and organization, as herein-after described and claimed, and in order that it may be fully understood reference is to be had to the accompanying drawings, in which—

Figure 1 is an inner side view of the left-hand member of a double-row lister-cultivator embodying my invention, the seat-plank being shown in section. Fig. 2 is a top plan view of the same with the seat-plank omitted. Fig. 3 is a vertical longitudinal section on the line III III of Fig. 2. Fig. 4 is a cross-section taken through the tongue on line IV IV of Fig. 2 and showing the cross-bar, the bearing-hangers carried thereby, the front crank-shaft mounted on the hangers, and the brace-arms between the cross-bar and the ground-wheel arms. Fig. 5 is a top plan view of a modified construction of a part of the machine. Fig. 6 is a side view of the construction shown in Fig. 5, but with the lever and toothed sector omitted and with a portion of the lower part of the machine added; and Fig. 7 is a vertical section taken on the line VII VII of Fig. 6.

As the members of a double-row cultivator are duplicates, a description of one will suffice for both.

In the said drawings, 1 designates the tongue, and 2 a bracket secured upon the same near its rear end. A frame consisting of cross-bar 3, side bars 4, and forwardly-converging bars 5 is secured at its rear side to

said bracket and at its front ends to the tongue as shown or in any other suitable or preferred manner.

6 designates bolts carried by side bars 4 of the frame, and 7 designates brackets secured to said frame by said bolts and provided with bearings 8 and 9, the former being preferably square and supporting the similar transverse cross-bar 10, which is held from longitudinal movement by spring-cotters 11.

12 designates arms clamped at the desired points on cross-bar 10, and forming a support at their lower ends for the customary ground-wheels 13, said arms having lugs 14, connected by braces 15 with a cross-bar 17, by means of bolts 16, extending through the holes 18 of bars 17, which occur in line with said arms.

19 designates a rock-shaft, rectangular in cross-section, journaled in bearings 9 of brackets 7, and adjustably secured on said rock-shaft, as shown or in any other suitable or preferred manner, are the shovel-beams 20, provided at their rear ends with the adjustable brackets 21, equipped with shovels 22.

23 designates arms which are also adjustably secured as shown or in any other suitable manner, on rock-shaft 19, and 24 adjustable extensions for said arms, said extensions carrying adjustably, as shown or in any other suitable or preferred manner, the cultivating-disks 25, it being understood in this connection that the special construction and arrangement of the cultivating appliances and their manner of attachment to the rock-shaft is well known in the art, and therefore not particularly described or claimed herein.

26 designates a crank-shaft journaled in bearings 27, depending from cross-bar 17, the crank-arms 28 of said shaft projecting upwardly. Crank-arms 29 are provided with rectangular sleeves 30, snugly embracing rock-shaft 19, and are clamped rigidly thereon, as at 31, and said crank-arms and crank-arms 28 are provided at their upper ends with bolts 32, pivotally engaging the side portions of the U-shaped frame 33, the frontends of said frame being pivotally connected by forwardly-converging links 34 to the crank-arms 35 of the rock-shaft 36, journaled in a bearing 37, secured to the lower side of the tongue. Said rock-shaft is also provided with a crank-arm 38, pivotally connected by a link 39 to the lever 40, pivoted, as at 41, to a frame 42, rigidly secured to the tongue, said frame having a

sector 43, engaged by a spring-actuated catch 44 on said lever.

In the drawings, which represent one member of a two-row cultivator, the frame 42 projects upwardly and inwardly, and the lever is correspondingly inclined, so as to bring it within convenient reach of the driver. Where the member is used as a single-row cultivator, it will be preferable to dispose the lever and said frame vertically, though of course this change of position would not affect the principle of construction involved. When the member is a part of a two-row machine, the side portions of frame 33 carry arch-bars 45 to provide loops to receive the usual seat-plank 46, and one end of said seat-plank is mounted on pivot-bolt 47, carried by the cross-bar 48, secured at its ends to the sides of frame 33. In this connection it should be stated that the left-hand gang of a two-row cultivator is usually that to which the plank is pivotally connected, and consequently is not ordinarily equipped with the arch-bars 45.

Under ordinary conditions the large amount of leverage given enables the driver to easily raise the cultivating appliances to inoperative position. To assist him in such operation, each gang may be provided with a pair of retractile springs 49, secured at their front ends to shaft 46 and at their rear ends to the pivots 32 of the crank-arms 29, the arrangement being such that rearward movement of frame 33 shall stretch or tension the springs in order that the latter may be in condition to assist in reélevating the cultivating appliances.

With the parts arranged as shown in the drawings it will be seen that the draft of the team tends to hold the cultivating appliances in the ground—that is to say, the draft of the team by tending to pull the tongue forwardly and from under the frame 33 actually, in conjunction with the resistance offered by the soil to the cultivating appliances, holds said frame 33 rearward with a yielding pressure. Coöperating with this draft of the team to hold said frame and the cultivating appliances depressed is the gravitational tendency of the parts named and also the weight of the driver. When it is desired to raise the cultivating appliances, the driver throws lever 40 forward and through the medium of link 39 moves frame 33 forward, this action of the frame rocking shaft 19 and raising the cultivating appliances. After the crank-shafts connecting frame 33 with the wheeled frame—viz., the tongue, the ground-wheels, and the connections between the latter and the tongue—have rotated until their crank-arms pass through the center of gravity the weight of the driver, frame 33, and the cultivating appliances is shifted forward of the vertical plane of said shafts, so as to hold the cultivating appliances elevated or inoperative, in which

position they are locked by the engagement of the catch 44 with sector 43. The reverse action of the lever results, of course, in swinging the rock-shafts rearward until their crank-arms pass their centers of gravity, after which the weight of the driver, frame 33, and the cultivating appliances effects the depression of the latter, the draft of the team, as hereinbefore explained, and the pull upon the lever tending to embed the cultivating appliances in the soil to the required depth.

Referring to Figs. 5, 6, and 7, which illustrate a modified construction of certain parts, 33^a designates the U-shaped frame, having a cross-bar 48^a, bolted to and upon lugs 48^b of brackets 48^b, secured to the frame 33^a, and 17^a designates a cross-bar similar to bar 48^a and likewise secured to frame 33^a, but at the forward end of the latter, and said cross-bar 17^a has a recess 17^b in its upper side to receive the depending rib *a* of a bracket A, bolted to and upon the said cross-bar, a link B pivoted at its rear end for vertical movement to said bracket being pivoted at its front end for lateral movement to the lever 40, so that the operation of said lever rearward or forward shall impart corresponding movement to the U-shaped frame.

C designates a cross-bar having an arched central portion *c*, fitting upon and bolted to the tongue 1, and connecting said cross-bar C to the brackets 7^a, depending rigidly from frame 3, are longitudinal braces D, the brackets 7^a being preferably secured to the outer side of frame 3 instead of its inner side, as in the preceding figures.

Depending rigidly from the ends of the cross-bar C are brackets E, and pivotally secured thereto are cranks 28^a, the equivalent of the crank-arms 28 of crank-shaft 26, the upper ends of cranks 28^a being pivoted to the U-shaped frame.

15^a designates braces, equivalents of braces 15, to connect the lugs 14 of ground-wheel arms 12 with the cross-bar 17^a.

It will be seen that the modified construction described is designed as a substitute for the parts 15, 16, 17, 26, 27, 34, 35, 36, 37, 38, and 39, as such modified form has been found in practice to stiffen and strengthen and generally improve the machine as well as reduce its weight and cost.

From the above description it will be apparent that I have produced a cultivator possessing the features of advantage enumerated as desirable in the statement of the object of the invention, and while I have illustrated and described its preferred embodiment it is to be understood that I reserve the right to make such changes in the form, proportion, detail construction, and arrangement of the parts as shall not be a departure from the principle of construction involved.

Having thus described the invention, what

I claim as new, and desire to secure by Letters Patent, is—

1. In a cultivator, a suitably-supported tongue; a lever and a rock-shaft thereon; a link pivotally connecting the lever and shaft; crank-shafts suitably journaled at a point fixed with relation to the tongue and underlying the same; a frame pivotally mounted on the crank-arms of said shafts; links pivotally connecting the frame with the rock-shaft; and cultivating appliances supported from one of the crank-shafts.

2. In a cultivator, a suitably-supported tongue; a lever and a rock-shaft thereon; a link pivotally connecting the lever and shaft; crank-shafts suitably journaled at a point fixed with relation to the tongue and underlying the same; a frame pivotally mounted on the crank-arms of said shafts; links pivotally connecting the frame with the rock-shaft; cultivating appliances supported from one of the crank-shafts; and springs for offering a yielding resistance to the depression of the cultivating appliances.

3. In a cultivator, a suitably-supported tongue; a lever and a rock-shaft thereon; a link pivotally connecting the lever and shaft; crank-shafts suitably journaled at a point fixed with relation to the tongue and underlying the same; a frame pivotally mounted on the crank-arms of said shafts; links pivotally connecting the frame with the rock-shaft; cultivating appliances supported from one of the crank-shafts; springs for offering a yielding resistance to the depression of the cultivating appliances; and means to lock the cultivating appliances in their depressed position.

4. In a cultivator, a tongue; a frame rigid thereon, ground-wheels connected and bearing a fixed relation to said frame; a lever and a rock-shaft on the tongue; a link pivotally connecting the rock-shaft and lever; crank-shafts supported from said frame; a frame pivotally mounted on the crank-arms of said shafts; links pivotally connecting the last-named frame with the rock-shafts; and cultivating appliances supported from one of said crank-shafts.

5. In a cultivator, a tongue; a frame rigid thereon; ground-wheels connected and bearing a fixed relation to said frame; a lever and a rock-shaft on the tongue; a link pivotally connecting the rock-shaft and lever; crank-shafts supported from said frame, a frame pivotally mounted on the crank-arms of said shafts; links pivotally connecting the last-named frame with the rock-shafts; cultivating appliances supported from one of said

crank-shafts, and retractile springs connected at their front ends to a point fixed with relation to the tongue and at their rear ends to a point longitudinally movable with relation to the tongue.

6. In a cultivator, a tongue; a frame rigid thereon; hangers depending rigidly from said frame; a cross-bar for the frame forward of said hangers; hangers depending from said cross-bar; a cross-bar carried by the first-named hangers; ground-wheel-carrying arms adjustable on the last-named bar; braces connecting said arms with the first-named cross-bar; a crank-shaft journaled in said first-named hangers; cultivating appliances adjustable on said crank-shaft, a crank-shaft journaled in the cross-bar hangers; a frame pivoted to the arms of said crank-shafts; and means for moving said last-named frame forward or rearward.

7. In a cultivator, a tongue; a frame rigid thereon; hangers depending rigidly from said frame; a cross-bar for the frame forward of said hangers; hangers depending from said cross-bar; a cross-bar carried by the first-named hangers; ground-wheel-carrying arms adjustable on said bar; braces connected to said arms at their lower ends and adjustably connected at their upper ends to the first-named cross-bar; a crank-shaft journaled in said first-named hangers; cultivating appliances adjustable on said crank-shaft, a crank-shaft journaled in the cross-bar hangers; a frame pivoted to the arms of said crank-shafts; a rock-shaft mounted on the tongue; links pivotally connecting the same with the last-named frame, a lever mounted on the tongue, a link pivotally connecting the lever and said rock-shaft, and means for locking the lever at the desired point of adjustment.

8. In a cultivator, a tongue, a frame secured thereto, a cross-bar secured to the tongue and suitably braced, a set of cranks supported from said cross-bar to operate forward and rearward, a rock-shaft suitably supported from said frame and provided with a set of crank-arms, cultivating mechanism supported by said shaft, a frame pivoted to the sets of crank-arms, a lever mounted on the tongue, and connections between the lever and crank-supported frame to transmit the lever movement to said frame.

In testimony whereof I affix my signature in the presence of two witnesses.

OLIVER H. CLOYD.
